FIG-13

UNITED STATES PATENT OFFICE

JOHN B. OHLSON, OF CHICAGO, ILLINOIS, ASSIGNOR TO THE VORTEX MFG. CO., OF CHICAGO, ILLINOIS, A CORPORATION OF ILLINOIS

DISPENSER

Application filed January 14, 1927. Serial No. 161,049.

This invention relates to a dispenser and particularly to a dispensing apparatus which is adapted to contain a plurality of nested articles such as paper drinking cups and to 5 conveniently discharge the same individually.

In many dispensers heretofore provided for this purpose the endmost article has been grasped by the user and pulled away from the article against which it is nested. Such 10 arrangements have often resulted in the inadvertent removal of two or more articles at one time and have been subject to the further disadvantage of not being readily adaptable to coin controlled dispensing.

15 It is an important object, therefore, of the present invention to provide a dispenser which overcomes these disadvantages and which at the same time completely incloses the articles to be dispensed, including the 20 endmost article.

It is a further important object of this invention to provide a dispensing device of the kind described embodying improved article gripping and removing means. It is another 25 object of this invention to provide a dispenser having an improved coin controlled operating mechanism.

It is also an important object of this invention to provide a dispenser of the kind described, wherein the various operating parts are of economical and durable construction and positive in operation.

Other and further important objects of this invention will be apparent from the 35 closures in the specification and the accompanying drawings.

This invention (in a preferred form) is illustrated in the drawings and hereinafter more fully described.

40 On the drawings:

Figure 1 is a front elevation of a dispenser embodying the principles of the present invention.

Figure 2 is a side elevation thereof.

45 Figure 3 is a bottom plan view with the bottom plate removed.

Figure 4 is a front elevation with the front plate removed.

50 Figure 5 is a side elevation with the side plate removed.

Figure 6 is a top plan view with the top plate removed.

Figure 7 is a side elevation looking to the left in Figure 4 with parts broken away.

Figure 8 is an enlarged fragmentary section on the line VIII—VIII of Figure 4. 55

Figure 9 is an enlarged fragmentary section on the line IX—IX of Figure 6.

Figure 10 is an enlarged fragmentary detail section of the coin released lever locking 60 mechanism.

Figure 11 is a section on the line XI—XI of Figure 10.

Figure 12 is a section on the line XII—XII 65 of Figure 10.

Figure 13 is a front elevation of a modified structure embodying the present invention with the front cover plate removed.

Figure 14 is a section on the line 70 XIV—XIV of Figure 13.

Figure 15 is an enlarged fragmentary detail of the lever controlling ratchet embodied in the modified construction shown in Figure 13.

As shown on the drawings:

The reference numeral 1 indicates a suitable inclosing casing in which dispensing apparatus embodying the present invention is mounted. The casing 1 is provided with a longitudinal gauge or side opening 2 which 80 is covered with transparent material affording a view of the nested articles 3, in this instance paper drinking cups, therethrough. The casing 1 is also provided with a slot 4 for the insertion of a coin for a purpose to be described hereinafter.

The dispensing apparatus which will be described hereinafter is actuated from the outside of the casing by manual reciprocal movement of the end 5 of an operating lever 6 which projects through a longitudinal slot 7 in the side wall of the casing 1. In order to prevent unauthorized tampering with the interior mechanisms a guard plate 8 is provided inside the slot 7, the lever 6 being 90 formed with a U-shaped portion 6^a to engage around said guard plate. The lever 6 is also provided with a lateral extension 6^b which cooperates with the coin control mechanism shown in detail in Figures 10, 11, and 12 in a 95 100

manner to be described hereinafter. Extending longitudinally of the interior of the casing 1 is a guide rod 9 on which the inner end of the lever 6 is slidably mounted, as clearly indicated in Figure 4. Said lever 6 is normally held at one end of the casing by means of a spring 10 secured to a boss 10^a on said lever at one end and secured at its other end to the top of the casing 1. In order to insure a full stroke of the lever 6 in each direction a suitable ratchet mechanism is provided which is clearly shown in Figures 5 and 9. This mechanism comprises a toothed bar 11 which is secured to the side wall of the casing 1 opposite the inner end of the lever 6, and cooperating with said toothed bar 11 is a spring actuated ratchet 12 which is pivotally mounted on a lateral extension 13 of the lever 6, as clearly shown in Figure 9. It will be noted from this construction that once movement of the lever is initiated in one direction it is necessary to move the same a sufficient distance so that the ratchet 12 clears the end of the toothed bar 11 and is permitted to swing to the opposite direction to permit of movement of the lever in the opposite direction, a full stroke in both directions thus being assured.

The nested articles to be dispensed by the apparatus of this invention, in this instance a series of nested paper drinking cups 3, are held in position inside the dispenser between a pair of trough-shaped guideways 14 which engage the edges of the articles at the ends thereof and which are preferably provided with teeth 14^a in their side walls to prevent undue displacement or slipping of said articles (Figs. 7 and 8). One of these members 14 is secured to the side wall of the casing 1 and the other is secured to a partition 14^b intermediate the side walls of the casing 1 (just to the right of the shaft as in Figure 3). The articles 3 are further held in position relative to the dispenser and toward one end thereof by means of a grooved roller 15 which is pivotally mounted on a carriage 16 slidably mounted in the casing 1 and normally urged toward one end thereof by a spring 17 secured to said carriage and to the end of the casing. Slidably mounted on the rod 9 is an article disengaging member which will now be described. This disengaging member comprises a laterally extending member 18 which extends around one edge of the partition member 14^b and which is provided at its free end with a flat spring member 18^a having a toothed end 18^b which engages the side wall of the article 3 preferably at a transverse seam 3^a of said article. The disengaging member further embodies a laterally extending member 19 which is provided with an extension 19^a extending through a longitudinal slot in the partition member 14^b and provided at its free end with a flat spring positioning member 19^b which engages the exterior of the end-

most article 3 to aid in positioning the same for gripping by the teeth 18^b, as clearly shown in Figure 3. The disengaging member above described is normally held in engagement with the endmost article 3 by means of a spring 20 secured at one end to a projection 21 on the member 19 and at its other end to the end of the casing 1 (Figs. 3, 6, and 9).

It will be apparent from the foregoing that downward movement of the lever 6 against the action of the spring 10 causes the inner end thereof to move along the shaft 9 and to move the disengaging member just described downwardly, whereby the endmost article which is gripped by the toothed member 18^a, 18^b is moved downwardly in the guideways 14 to a discharge position which is clearly shown in dotted lines in Figure 4. When in this discharge position the closed end of the article projects through a slot 22 formed in the end of the casing 1 guiding baffles 23 preferably being provided to assure the entrance of the closed end of the article into the slot. In order to cushion the engagement between the inner edge of the lever and the disengaging member at the time of the operation just described a cushioning spring 24 is preferably provided, as clearly shown in Figure 4. It will be apparent that when the operation just described is completed and the article is moved to discharge position with its closed end projecting through the slot 22 that release of the lever 6 will cause the same to be returned to its normal position shown in Figure 4 by the action of the spring 10. At the same time the disengaging member 18, 19 will be moved to its normal position in engagement with the endmost article 3 by the action of the spring 20, this movement being, of course, independent of the return movement of the lever 6. It will be further noted that in view of the fact the articles 3 as a whole are maintained in the same position relative to the casing 1 and the guideways 14 by the roller 15 and the spring 17 that the amount of return travel of the disengaging member will be different in each case.

Although it is evident that the dispenser of this invention is a completely operative device, as I have previously described the same herein, I have further provided means whereby the actuation of the lever 6 may be coin controlled in order to adapt the machine for coin and slot vending of the contained articles, such as nested drinking paper cups. The coin control apparatus which I have provided for this purpose is shown in detail in Figures 10, 11, and 12. The laterally extending member 6^b on the lever 6, previously referred to, extends between spaced members 25 and 26 which project inwardly from the wall of the casing 1 at either side of the coin slot 4. The member 26 is provided with an opening at its lower edge through which projects a rounded end detent 27, said detent 27

being pressed through said opening by a flat spring 28 secured to the side of said member 26, as shown in Figures 11 and 12. Said detent 27 projects through an elongated opening 29 in the member 6^b, said member 6^b also being provided with a coin engaging catch or projection 6^c. When a coin 30 is inserted through the slot 4 it falls into the position shown in Figure 11 so that when the lever is moved downwardly the coin engaging portion 6^c engages the upper edge of the coin 30 and pushes the same downwardly, thus forcing the detent 27 to the left in Figure 11 so that the rounded edge thereof may be engaged by the upper edge of the member 6^b at the opening 29 and pushed out of the way of said member to permit the lever 6 to be moved downwardly throughout its stroke to disengage the article 3 and move it to discharge position. As will be noted the upper side of the coin engaging catch or projection 6^c is beveled so that it will move the detent 27 to one side when the lever is returned to position, thus permitting the parts to again automatically assume the position shown in Figure 11 after the article has been disengaged and moved to discharge position.

In Figures 13 to 15, inclusive, I have shown a modified form of apparatus embodying the present invention wherein a base 31, preferably of stamped metal, affords a support for a suitable inclosed casing not shown. Formed on the base 31 are arcuate partition members 32 and 33 which afford guideways 34 for a plurality of nested paper drinking cups similar to the articles 3 and which I have designated in this modification by the reference numeral 35. These are provided for disengaging the endmost of these articles 35 and moving the same along the guideways 34 to a discharge position with its closed end projecting through a slot not shown in a member 36 projecting from the base 31 as shown in Figure 13. For this purpose I have provided a lever member 37 which is pivotally mounted on a stud 38 supported on the base 31 and which is provided at its free end with a resilient guide member 39 of spring metal or the like engaging the side wall of the endmost article 35. Said lever 37 also carries a lateral extension 40 which is provided at its free end with a pointed disengaging member 41 which engages in the wall of the article, preferably adjacent the seam 35^a (corresponding to the seam 3^a therein). In order to actuate the lever member 37 and the article disengaging apparatus associating therewith I have provided an additional lever member 42 which extends beneath the lever member 37 and which is rotatable on the stud 38 by an arcuate handle or lever 43. Said lever member 42 is provided with a lateral stud or projection 44 which engages an edge of the lever 37 so that when said lever member 42 is moved in a clockwise direction the member 37 and

attendant disengaging apparatus is carried therewith. The projection 44 on the lever member 42 is normally held resiliently in contact with the lever member 37 through the action of a spring 45 coiled about the stud 38 and having its free ends respectively secured to opposite sides of the lever members 37 and 42.

In order to insure a full stroke of the lever member 42 in either direction once the movement thereof is initiated, I have provided a ratchet mechanism 46 (Fig. 15) which cooperates with a toothed flange 47 in the same manner as the ratchet 12, previously described, to assure a full stroke movement of the lever in either direction.

In order to hold the articles 35 in position relative to the guideways 34, I have provided a lever member 48 which is pivoted at one end at the base of the stud 38 and normally urged in a counterclockwise direction by a spring 49 secured to said lever and to the base 31. The free end of the lever 48 is provided with upwardly extending portions 50 and 51 which engage the edges of the endmost article regardless of the extent of the nest of articles and hold said articles in proper relative position.

It will be apparent from the foregoing description that I have provided a dispensing apparatus which is of relatively simple and economical construction and which will effectively operate to dispense articles, such as paper drinking cups, individually and without the necessity of the operator grasping the endmost article when it is in contact with the other articles. The major portion of the operating mechanism may be inclosed and the articles themselves are also, of course, inclosed. This prevents accidents to the operating mechanism and renders the device highly sanitary. While this apparatus is particularly designed for use in the dispensing of articles embodying a transverse seam, it will be apparent that it may also be effectively used to dispense seamless articles since the article engaging members may be adjusted to engage directly in the wall of the endmost article to disengage the same.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. In a dispenser adapted to carry a plurality of nested seamed articles, a resiliently supported roller for supporting the articles, guideways engaging the articles at opposite sides, slidable means for temporarily engaging the seam of the endmost article to disengage the same from the remainder of the articles, a slotted casing inclosing said arti-

cles and said means, and reciprocable means projecting through the casing for sliding said first mentioned means to disengage an article and move the same along the guideways to discharge position at the slot in the casing.

5. 2. In a dispenser a casing adapted to carry a plurality of nested articles each of which is provided with a transverse seam, resiliently supported roller means for holding the articles in a nested position within said casing, and means for successively engaging the endmost articles at the seams to disengage the same individually from the remainder of the articles.

15. 3. In a dispenser a casing adapted to carry a plurality of nested articles each of which is provided with a transverse seam, guideways in said casing engaging the sides of the articles, resiliently supported carriage in said casing, a roller thereon for supporting the articles, and means for successively engaging the seam of the endmost article to disengage the same individually from the remainder of the articles.

20. 4. In a dispenser for a plurality of nested articles, guideways engaging the sides of the articles, a grooved roller engaging the side of the endmost article adjacent one of said guideways, and a spring supported carriage supporting the roller for holding the same against the endmost article to support the articles in a nested position.

35. 5. In a dispenser a casing for carrying a plurality of nested articles, guideways in said casing engaging the sides of the articles, a grooved roller engaging the side of the endmost article adjacent one of said guideways, a carriage slidably mounted in said casing and supporting said roller, resilient means 40 associated with the carriage for holding the roller against the endmost article to support the articles in a nested position, and means for engaging the endmost article to disengage the same from the remaining articles 45 and move it along the guideways to a discharge position projecting from said casing.

50. 6. In a dispenser a casing for carrying a plurality of nested articles, guideways in said casing engaging the sides of the articles, a grooved roller engaging the side of the endmost article adjacent one of said guideways, and resilient reciprocable means in said casing for engaging the endmost article to disengage the same from the remaining articles 55 and move it along the guideways to a discharge position in said casing.

60. 7. In a dispenser a casing adapted to carry a plurality of nested articles each of which is provided with a transverse seam, a spring supported carriage in said casing for holding the articles in place in said casing, and toothed means for successively engaging the endmost article at the seam to disengage the 65 seam individually from said nested articles

and move it into a projecting discharge position in said casing.

8. In a dispenser, a casing adapted to carry a plurality of nested articles each of which is provided with a transverse seam, roller means for resiliently supporting the nested articles in place within said casing, and resilient toothed means for engaging the endmost article adjacent the seam to disengage said article individually from the remainder 70 of the articles.

9. In a dispenser a casing, means for supporting a plurality of nested articles in said casing, spring controlled means in said casing for separating the endmost article from 80 said nested articles, operating means for said spring controlled means, and means for retracting the operating means independently of said spring controlled means.

10. In a dispenser, a casing, a resiliently supported roller adapted to carry a stack of articles each of which is provided with a seam, and means for successively engaging the endmost articles at the seams to disengage the same individually from the stack. 85

In testimony whereof I have hereunto subscribed my name.

JOHN B. OHLSON.
